CLAIM

The ornamental design for an electronic component housing, as shown.

DESCRIPTION

FIG. 1 is a perspective view of an electronic component housing showing our new design, depicting the front, top and one side thereof;

FIG. 2 is an elevational view, showing the front of the electronic component housing;

FIG. 3 is an elevational view showing one side thereof;

FIG. 4 is an elevational view showing the rear thereof;

FIG. 5 is a bottom plan view thereof; and,

FIG. 6 is an elevational view showing the side opposite that shown in FIG. 3.
